UNITED STATES PATENT OFFICE.

STERNER ST. P. MEEK, OF PHILADELPHIA, PENNSYLVANIA.

COMBUSTIBLE COMPOSITION.

No Drawing.

Application filed January 18, 1926. Serial No. 82,120.

(GRANTED UNDER THE ACT OF MARCH 3, 1883, AS AMENDED APRIL 30, 1928; 370 O. G. 757.)

The invention described herein may be manufactured and used by or for the Government for governmental purposes without the payment to me of any royalty 5 thereon.

The subject of this invention is a combustible composition intended primarily for use in tracer projectiles for signalling, illuminating, or like purposes.

10 The principal object of the invention is to impart greater visibility, brilliance and luminosity to the combustible by using an element or elements which occur in abundance and which may replace other elements 15 whose scarcity may assume serious proportions. I therefore propose to use zinc compounds either alone or in combination with other substances.

20 The zinc compounds may be used in the form of oxygen carriers, as zinc oxide, zinc peroxide, zinc nitrate, etc., or in the form of a fuel for decreasing the rate of burning of the mixture while at the same time increasing the brilliance as by using it in the form 25 of zinc thiocyanate, zinc acetate, or zinc oxalate; or the zinc may be added merely in the form of an inert substance to increase the brilliance, as for example, zinc chloride, zinc sulphide, etc.

30 As an example of the use of zinc compounds in the form of oxygen carriers, the following formulæ are given:

	Parts.
Strontium nitrate	60
35 Zinc nitrate	60
Sodium oxalate	40
Sodium nitrate	10
Magnesium	8
Calcium resinate	46
40 Barium nitrate	28
Zinc peroxide	60
Barium oxalate	50
Sodium nitrate	10
Magnesium	8
45 Aluminum	34
Calcium resinate	12
	80

The following formula is a typical example of the use of a zinc salt as a fuel.

	Parts.
Barium nitrate	15
Barium peroxide	50
Calcium resinate	12
Magnesium	12
Zinc thiocyanate	20
	12

55 Of the use of a zinc salt as an inert substance for increasing the brilliance of the combustible, the following are examples:

	Parts.
Barium peroxide	20
Barium nitrate	60
Magnesium	2
Calcium resinate	7
Zinc chloride	3
	2

65 and

	Parts.
Strontium nitrate	100
Zinc oxalate	10
Sodium nitrate	8
Magnesium	34
Aluminum	70
Calcium resinate	12
Zinc chloride	28
	10

I claim:

1. A tracer mixture comprising magnesium, a metal resinate, a zinc compound and a suitable oxygen carrier.
2. A tracer mixture comprising magnesium, a resinous binder a zinc compound and a suitable oxygen carrier.
3. A tracer mixture comprising aluminum magnesium, a metal resinate, a zinc compound and a suitable oxygen carrier.
4. A tracer comprising aluminum, magnesium, a binder, a zinc compound and a suitable oxygen carrier.
5. A tracer composition including a highly combustible metal, a zinc compound and a metallic resinate binder.
